UNITED STATES PATENT OFFICE

EDWARD T. JOHNSON, OF GREENFIELD, MASSACHUSETTS, ASSIGNOR TO THE NEW ENGLAND BOX COMPANY, OF GREENFIELD, MASSACHUSETTS, A CORPORATION OF MASSACHUSETTS

WIRE-BOUND BOX AND METHOD OF MAKING THE SAME

Application filed December 23, 1929. Serial No. 416,071.

My invention relates to new and useful improvements in wire bound boxes and the method of making the same, and has for an object to provide a box that, although made of 5 relatively thin material, will provide the maximum strength and, at the same time, will be relatively light in weight and tight about the edges and corners.

A still further object of the invention is to 10 provide a wire bound box that may be made and shipped in the form of a mat together with end pieces and strips so as to take up but little space when in its knocked-down form.

15 Still another object of the invention is to provide a wire bound box wherein after the box is assembled, the respective edges, that is, where the adjacent edges of the bottom, sides and cover meet, will be so tightly fitted 20 that material may be shipped in them that would otherwise drop out or leak from the several edges of the ordinary box.

Still another object of the invention is to 25 provide a box that may be shipped in its knocked-down form before assembly, the box comprising simply a mat, two end pieces, and four longitudinal reinforcing strips that are to be loosely inserted, so that the meeting edges of the box will be very close fitting 30 when in bound-up form.

Still another object of the invention is to 35 provide a box that may be made of relatively light material and, at the same time, so stitched and formed that it will be exceedingly strong in service, light in weight and well sealed along its various edges.

With these and other objects in view, the 40 invention consists in certain new and novel arrangements and combination of parts, as will be hereinafter more fully described and pointed out in the claims.

Referring now to the drawings showing a preferred embodiment,

45 Fig. 1 is a plan view of the mat showing the outside;

Fig. 2 is an edge view;

Fig. 3 is a view of the mat in its folded position and before the end pieces are inserted;

50 Fig. 4 is a detail of one of the ends;

Fig. 5 is an enlarged longitudinal cross sectional view of the box when in its completed state;

Fig. 6 is a sectional view taken on the line 6—6 of Fig. 5;

Fig. 7 is a perspective of one of the four reinforcing strips;

Fig. 8 is a perspective of the box, parts being broken away to show the corner construction;

Fig. 9 is a perspective showing how the reinforcing strips fit and rest on the corners of the end pieces, when assembled.

Referring now more particularly to the several views and for the moment to Fig. 1, there will be seen the mat which is made up of wooden pieces or sections, wherein a piece 1 is a side, 2 is the bottom, 3 is a side and 4 is the top. That is, these several pieces of the mat, when shaped to form, will be these respective parts of the completed box. As also may be seen from Fig. 1, any of these several pieces that form the top, sides and bottom may, in turn, be made up of strips or may be one piece, as desired.

In the present instance, I have shown four rows of stitching 5 for holding the mat together, the material being preferably wire, which is held in place by the small staples 6, and this wire stitching will be placed on with an ordinary box wire stitching machine.

It will be noticed that the two outer rows of stitching also hold in place a number of wooden cleats 7, and taking for instance the first piece of the mat, that is, one of the sides, as shown to the left of Fig. 1, two wooden cleats are stitched on the under or inner surface and near the opposite ends of the same. These cleats are tongued at their opposite ends, as at 8, so that the tongues, in turn, will cooperate with grooves 9 formed in the ends of the further wooden cleats 7 stitched on the bottom piece. In the same way, similar cleats are on the next piece and on the sides and top pieces, so that when the mat is folded or shaped to form, as shown in the remaining views, these wooden cleats will all be locked with the well-known tongue and groove formation.

As will also be noticed in Fig. 1, when these

several parts, that is, the sides, bottom and top, are stitched to form the mat, there is a relatively small space 10 between the adjacent edges of the several pieces, so that the mat can be folded up to box-like form.

As may also be noticed in Figs. 1 and 3, the rows of wire stitching have their outer ends projecting, as at 11 and 12, so that after the box is fully shaped and packed, these respective overlapping ends 11 and 12 may be tightly twisted around each other, so as to pull the box tightly together and tie the same.

Having understood how the mat is formed, reference now will be made to the end pieces, 15 as shown in Fig. 4. Here, the end 13 is clearly shown and this, in turn, may be made up of separate pieces 14 and held by the strips 15, or this end piece might be made up of one piece rather than these sections, if so desired.

It will be understood that there will, of course, be two ends and they are identical in structure, so that a description of the one is a description of the other.

One of the important contributing factors 25 to the invention is that the four corners of this end piece are beveled or cut-off, as at 16, so that triangular reinforcing strips 17 may extend from the one end piece to the other end piece and fit in these several cut-off corners. Of course, the base 18 of each reinforcing strip will lie adjacent a beveled corner, so that when all of them are in position, they will appear as shown in Fig. 6.

In assembling the box, the mat will be 30 turned over or reversed from the position shown in Fig. 1 and folded as shown in Fig. 3, and the partly assembled box will be stood on its one end and an end piece nailed to the cleats 7. The two bottom reinforcing strips 17 are then slipped into place, so that the respective bases of these reinforcing strips will fit adjacent the cut-off corners of the end piece and abut the end cleats. The box will be set up on its other end, the other 35 end piece nailed to its respective cleats and then the two remaining reinforcing strips 17 placed in position, so that we now have the two end pieces nailed to the respective cleats and the four reinforcing strips running the 40 entire length of the box and their ends resting on the cut-off corners of the end pieces and abutting the cleats to thus brace and strengthen the box throughout and, in reality, form a skeleton frame.

These reinforcing strips 17 may be of wood or metal, as they are not necessarily nailed to the end pieces but simply rest thereon.

In Fig. 9, I have shown what the skeleton frame will look like without the mat shaped therearound and it will be appreciated how this skeleton frame will strengthen the entire box.

There are other advantages, however, in using the end pieces with the cut-off corners 65 on which rest the reinforcing strips, that

assist in the strengthening of the box, and these further advantages are that after the box is packed and the ends of the wire stitching 11 and 12 are respectively secured to each other, these longitudinal meeting edges 70 of the box, that is, along the sides at both the top and bottom, are tightly fitted together and clasp the surfaces of the reinforcing strips 17, which are really of wedge-shape formation. In other words, after the box is loaded and the top or cover closed and the ends of the wire strips are grasped in a special tool for pulling the wire stitching tight and then twisting the same, both the sides, bottom and cover are tightly pulled toward 75 each other and, of course, inwardly against the four triangular strips that extend across the edges, thus making it possible to ship material in this box that would leak or spill or flow through the several edges of an ordinary wire-bound box.

Thus, it will be seen that not only have I produced a box that is easy to construct, easy to assemble and exceedingly well braced between its ends but, at the same time, have provided a box wherein there will be no leakage or opening along its edges, which is so often the case with the ordinary wire bound boxes which are made of relatively light material and not closely fitted.

From the foregoing, it will be seen that I have devised a box wherein the cleats, sides, cover and top may be quickly stitched on an appropriate machine in the factory, and wherein the end pieces may have the corners quickly beveled to receive four strips that are packed with the mat, so that the parts of the box may be shipped in great quantities in their knocked-down form and occupy but little space.

Furthermore, the consumer of the boxes may quickly assemble them, it being only necessary to nail the end pieces to the cleats and insert the four longitudinal strips, all of which may be done in the course of a few 110 minutes.

Finally, after the box is packed, the ends of the wire stitching may be twisted by a suitable tool or brace, as is the ordinary practice, and the box in its completed form will be 115 tightly bound and tightly reinforced. Also, the meeting adjacent edges throughout will tightly grip the angular inserted reinforcing strips and thereby prevent any of the material within the box from leaking out or spilling along any of these edges.

Many slight changes might be made without in any way departing from the spirit and scope of the invention.

Having thus described my invention, what I claim as new and desire to secure by Letters Patent is:—

1. A wire bound box comprising a mat formed of a bottom, two sides and a cover, the pieces of the mat being stitched together 120

with wire, two end pieces, the said end pieces having their corners cut off, the mat when shaped nailed to said end pieces, four longitudinal pyramidal strips having their bases lying adjacent the respective cut-off corners of the end pieces, the mat tightly encircling said longitudinal strips and the ends of the wire stitching adapted to be respectively secured to each other to thereby tightly bind the box together.

2. A wire bound box comprising a bottom, sides and a cover stitched together in the form of a mat, two end pieces, the said end pieces having their corners beveled at right angles to diagonal lines drawn from the respective corners, triangular corner strips extending from the opposite ends of the box and situated at the four respective corners, the bases of the respective triangular strips lying flush with the beveled edges of the corners to thereby form four relatively square edges, the opposite ends of the wires forming the stitching adapted to be respectively fastened to each other when the cover is down to thereby reinforce the box and tightly hold the four edges together.

3. A wire bound box comprising a bottom, sides and a cover stitched together in the form of a mat, two end pieces, each having their corners cut to receive longitudinal reinforcing strips extending from end to end of the box, said strips being triangular in shape and having their apexes extending outwardly from the box, the end pieces being nailed to the mat when the same is in its shaped position, the ends of the respective bands of the wire stitching secured to each other when the cover is down to thereby reinforce the box and hold the respective adjacent edges of the sides, cover and bottom tightly against the diverging walls of the said reinforcing strips.

4. A wire bound box made up of a mat, said mat comprising sides, bottom and cover, wooden strips located near the opposite edges of the said pieces of the mat and the said pieces stitched to the sides, bottom and cover of the mat, two end pieces, said end pieces nailed to said strips when the mat is formed in the shape of the box, the said end pieces having their corners beveled, reinforcing strips extending between the ends and along the respective top and lower edges of the box, and wire extending completely around the box when in its finished shape and the respective edges of the pieces of the mat tightly fitting against the said longitudinal reinforcing strips.

5. A wire bound box comprising two end pieces having their corners beveled, the sides and bottom nailed to said end pieces, longitudinal triangular reinforcing strips placed on the beveled corners with their apexes extending outwardly, said strips fitting between the adjacent respective edges of the sides, bottom and top, and wire strips secured

around the box to tightly jam the adjacent edges of the respective pieces against the respective walls of the triangular reinforcing strips.

6. A box comprising sides, bottom and top and their respective edges being slightly spaced from each other, end pieces having their four corners beveled, triangular reinforcing strips extending between the two end pieces and the apexes of the reinforcing strips fitting between the respective spaced sides, bottom and cover, and wire strips passed around the box to tightly draw the spaced edges against the sloping walls of the triangular pieces.

7. A box comprising a mat, said mat formed of the sides, bottom and cover, all of which are stitched together and with the parts slightly spaced from each other, end pieces secured to the mat when the latter is shaped in the form of a box, the said end pieces having their corners cut to loosely receive triangular reinforcing strips extending throughout the length of the box, the wires of the stitching adapted to be secured to each other to thereby reinforce the box, hold down the cover, and tightly force the respective adjacent edges of the box against the respective walls of the triangular-shaped reinforcing strips.

8. The method of forming a box which consists in stitching the sides, bottom and cover in the form of a mat, wooden cleats also stitched longitudinally of the mat, end pieces with their edges beveled, fitting the mat around the end pieces and nailing the end pieces to the cleats, inserting four longitudinal triangular strips so that their ends respectively rest on the said beveled portion of the end pieces, and twisting the respective ends of the wire stitching together to tightly bind the box together.

9. The method of making a wire bound box which consists in stitching the sides, bottom and cover in the form of a flat mat with the said parts slightly spaced from each other when in their flat condition, wooden cleats also stitched longitudinally of the mat, end pieces having their respective four corners beveled, fitting the mat around the end pieces and nailing the ends to the said cleats, loosely inserting the four longitudinal strips so that their ends rest on the beveled corners of the end pieces and tightly twisting the respective ends of the stitching together when the box is closed to thereby reinforce the box and to hold the cover down and to pull the respective side edges of the box tightly together.

In testimony whereof I affix my signature,

EDWARD T. JOHNSON.
